UNITED STATES PATENT OFFICE.

ABE WEST, OF ST. CLOUD, MINNESOTA.

TOBACCO-BALING PRESS.

Application filed January 8, 1927. Serial No 159,869.

This invention relates to baling presses, and has for one of its objects to provide a device of this character which shall include a box so constructed as to permit the material to be baled to be readily placed therein and the baled material to be readily removed therefrom, and means by which the capacity of the box may be varied so as to permit bales of different lengths to be made.

10 A further object of the invention is to provide a baling press wherein the plunger shall be slidably supported by a carrier or table mounted for movement into an operative position over the box and into an inoperative position laterally beyond the box.

15 A further object of the invention is the provision of a baling press which shall include means adapted to releasably secure the plunger carrier or table in inoperative position, means adapted to releasably secure the plunger carrier or table in operative position, and a plunger actuating lever normally occupying an upwardly inclined position and adapted when in said position to render said 25 second means ineffective.

20 A further object of the invention is to provide a baling press which shall include means mounted upon the plunger carrier or table for normally supporting the plunger in 30 raised position.

35 A still further object of the invention is to provide a baling press wherein the lever will when released after its actuation to effect the downward movement of the plunger release the plunger carrier or table, wherein the plunger will be returned to its normally elevated position prior to the release of the carrier or table, and wherein the carrier or table will then be swung into and latched in inoperative position.

40 With the foregoing and other objects in view, the nature of which will become apparent as the description proceeds, the invention consists of the construction, combination and arrangement of parts hereinafter fully described and claimed, and illustrated in the accompanying drawings, wherein:

45 Figure 1 is a view in side elevation of a baling press constructed in accordance with my invention, the plunger carrier or table being shown in operative position and the plunger and lever in depressed position.

50 Figure 2 is a similar view looking at the opposite side of the baling press and showing the plunger and lever in elevated position,

Figure 3 is a sectional view taken on the vertical plane indicated by the line 3—3 of Figure 1,

55 Figure 4 is a top plan view of the baling 60 press with the plunger carrier or table in a position midway between its operative and inoperative positions,

Figure 5 is a detail sectional view taken on the vertical plane indicated by the line 65 5—5 of Figure 1,

70 Figure 6 is a view in side elevation of the box of the baling press illustrating the application of the means by which the length of the box may be varied, and

Figure 7 is a top plan view of the box as shown in Figure 6.

Corresponding and like parts are referred to in the following description, and designates in the several views of the accompanying drawings, by similar reference characters.

75 In the drawings, 1 designates the base and 2 the box of the baling press. A portion of the base 1 constitutes the bottom 3 of the box 80 2. The ends 4 of the box 2 have a fixed position with respect to the bottom 3, and the sides 5 of the box are secured to the bottom by 85 hinges 6. Spring latches 7 which are secured to the upper edges of the ends 4 and engage the upper edges of the sides 5, releasably secure the sides in closed position, and the sides are provided at their ends with flanges 8 which contact with the outer faces of the ends 4 when the sides are in closed position. The 90 box 2 also comprises extension ends 9 which rest upon the bottom 3 and contact with the inner faces of the ends 4, and are secured to the ends 4 by straps 10 and screws 11. Side 95 extensions 12 which rest upon the upper edges of the sides 5, are removably secured to said sides 5 by inner straps 13 and outer straps 14. The straps 13 are secured to the side extensions 12 and contact with the inner faces of the sides 5, and the straps 14 are secured to the sides 5 and contact with the outer faces of the side extensions 12. The straps 14 are reinforced by braces 15 which are secured to said parts and to the sides 5.

100 The press is especially adapted for baling tobacco, and as the sides 5 are hinged to the base 3 and the side extensions 12 detachably secured to the sides, the tobacco to be baled may be readily inserted in the box 2 and the baled tobacco readily removed therefrom. 110 The wrapper 16 for the baled tobacco is placed in the box 2 in contact with the bot-

tom 3 and sides 5 and with its free end portions positioned between the sides and the side extensions 12. The elements 17 for tying the bale are positioned between the 5 wrapper 16 and the bottom 3 and sides 5, and the sides are provided in their upper edges of the sides with recesses 5^a for the reception of the tying elements. After the bale is formed, the free end portions of the wrapper 16 10 are folded over the bale, and thereafter the ends of the elements 17 are tied together.

To permit bales of different sizes to be formed, there are provided filler pieces 18 which are adapted to be inserted in the box 15 2 in parallel relation with the ends 9, and in width and length are similar to the corresponding dimensions of the ends. The filler pieces 18 are adapted to be secured in place by bolts 19 which are firmly fixed thereto and 20 pass freely through openings 20 in the ends 9, and by winged nuts 21 mounted upon the bolts for contact with the outer faces of said ends. The filler pieces 18 may be secured in place in contact with the inner faces of the 25 ends 9 or they may be secured in place at different distances from the ends. When the filler pieces 18 are spaced from the ends 9, spacers 20 are inserted between these parts. Each spacer 20 comprises a plurality of strips 30 23 of a length equal to the corresponding dimension of the ends 9 and filler pieces 18. The strips 23 are connected together by hinges 24 in a manner to permit the spacers 20 to be arranged in fully extended or partly 35 or fully folded condition, whereby to enable the filler pieces 18 to be spaced at different distances from the ends 9.

A post or standard 25 is secured to the base 1 adjacent an end of the box 2, and braces 40 26 therefor are secured thereto and to the base. A carrier or table 27 is pivoted as at 28 to the standard 25 for movement about a vertical axis into an operative position over the box 2 and for movement into an inoperative 45 position at one side of the box. The carrier or table 27 comprises a lower member 29 and an upper member 30 which are spaced by bars 31 and secured together by bolts 32 and diagonal braces 33. The members 29 and 30 50 are provided with openings 34 for the slideable reception of the bar 35 of a plunger 36. The plunger 36 is normally supported in a raised position by a weight 37 which is slideably mounted between guides 38 fixed to the members 29 and 30 and passing through 55 openings 39 therein. Cables 40 connect the weight 37 to the bar 35 and pass over direction pulleys 41 which are supported by brackets 42 secured to the member 30. The 60 upper end of the bar 35 is forked as shown at 43, and journaled in said end thereof is a roller 44. A roller 45 is journaled on the member 30 and contacts with said bar 35 for the purpose of insuring the free movement 65 of said bar with respect to the carrier or

table 27. The table 27 is adapted to be secured in operative position by a latch which comprises a bolt 46 secured to the member 30 and a catch 47 slidably secured to the standard 25 by screws 48. The catch 47 is yieldingly supported in active position by a spring 49 which is secured at one end thereto and at the other to a bracket 50. The bracket 50 is secured to the standard 25 for vertical adjustment with respect thereto by screws 51, 70 75 the adjustability of the bracket permitting the tension of the spring 49 to be varied. When the catch 47 is retracted or moved downwardly out of engagement with the bolt 46, the carrier or table 27 is swung into inoperative position by a spring 52 which is secured to the standard 25 and bears against the carrier or table. Immediately upon reaching its inoperative position, the carrier or table 27 is secured in this position by a 80 latch which consists of a bolt 53 secured to the member 29 and a catch 54 secured to an arm 55. The arm 55 is secured to the braces 26, and is supported by braces 56 secured thereto and to the standard 25. The carrier or table 27 is provided with a lug 57 which 85 fits in the free end of the spring 52 when the carrier or table is in operative position. The catch 47 is adapted to be retracted against the tension of the spring 49 by a shaft 58 which 90 is connected to the standard 25, and is provided at one end with a crank 59 pivotally engaged with the catch and at the other end with a crank 60 positioned for engagement 95 by a trip 61 carried by a lever 62.

The lever 62 is made in two parts or sections 63 and 64. The lever section 63 is pivoted to the standard 25 by a bolt 65. The upper end of the standard 25 is provided with a recess 66 for the reception of the lever section 63, and the bolt 65 is carried by the braces 26 and angle irons 67 which latter are secured to and reinforce the standard 25. The shaft 58 is journaled in one of the braces 26 and one of the angle irons 67. The lever section 63 is pivoted between its ends to the standard 25, and to what may be termed the rear end thereof is secured a weight 68 which normally supports the lever in any upwardly and forwardly inclined position. The lever 64 is connected to the lever section 63 for adjustment toward and from a pivot 65, and this connection is established by a yoke 69 secured to the lever section 63 and slidably embracing the lever section 64 and a yoke 70 secured to the lever section 64 and slidably embracing the lever section 63. A roller 71 is carried by the yoke 70 and contacts with the lever section 63. The lever 62 is employed to effect the lowering or depressing of the plunger 36, and in view of the adjustable connection of its section 64 with its section 63 its effective length may be varied so as to permit a person to bring various pressures to bear upon the contents of the box 2. The 100 105 110 115 120 125 130

lever section 63 is provided with an arcuate portion 72 for contact with the roller 44.

In practice, the tying elements 17 and wrapper 16 are placed in the box 2 in the manner shown in the drawings. After this has been done the side extensions 12 are put in place, the tobacco placed in the box 2, and a follower 73 placed upon the tobacco. The carrier or table 27 is then swung into operative position in which position it is secured by the bolt 46 and catch 47. The lever 62 is next pulled downwardly with the result that the follower 73, plunger 36 and plunger rod 35 are forced downwardly and the weight 37 elevated. After the bale is formed, the lever 62 is released, and immediately thereon it is returned to its normally elevated position by the weight 68, and at the same time the plunger 36 is moved into its normally elevated position upon the weight 37. Immediately on the movement of the lever 62 into its normally elevated position, the trip 61 contacts with the crank 60 of the shaft 58. This rocks the shaft 58 in a direction to retract the catch 47. The carrier or table 27 is now released, and the spring 52 swings it into its inoperative position in which position it is secured by the bolt 53 and latch 54. The free ends of the wrapper 16 are now folded over the tobacco and the ends of the elements 17 are then secured together. The bale thus formed and wrapped and secured together may now be removed from the box 2.

It should be understood that the drawings are merely illustrative and do not pretend to give exact proportions. Furthermore, the said drawings are illustrative of a preferred construction, it being my expectation that various changes and modifications may be made without departing from the spirit and scope of my invention.

What is claimed is:—

1. A baling press comprising a box, a carrier, means for supporting the carrier for movement into operative position over the box and into inoperative position laterally beyond the box, means for releasably securing the carrier in the first of said positions, a plunger mounted on the carrier, a plunger operating lever adapted when in one position to render said means ineffective and means for moving the carrier into the second of said positions when said second means is rendered ineffective.
2. A baling press comprising a box, a carrier, means for supporting the carrier for movement into operative position over the box and into inoperative position laterally beyond the box, a latch for holding the carrier in the first of said positions, a plunger slidably mounted on the carrier, means for normally supporting the plunger in raised position, a lever for depressing the plunger, means adapted to be operated by the lever to render the latch ineffective, and means adapt-

ed to move the carrier into the second of said positions when the latch is rendered ineffective.

3. A baling press comprising a box, a carrier, means for supporting the carrier for movement into operative position over the box and into inoperative position laterally beyond the box, a plunger mounted on the carrier, plunger operating means, a latch for supporting the carrier in the first of said positions, a latch retracting member adapted to be operated by said plunger operating means, and means adapted to move the carrier into the second of said positions when the latch is retracted.

4. A baling press comprising a box, a standard rising above the box, a carrier pivoted to the standard for movement into operative position over the box and into inoperative position laterally beyond the box, a latch carried by the standard for holding the carrier in the first of said positions, a second latch carried by the standard for holding the carrier in the second of said positions, a plunger movably mounted on the carrier, means normally supporting the plunger, a plunger actuating lever, a weight secured to the lever and adapted to normally support it in elevated position, means for retracting said first named latch and operable by the lever, and means for moving the carrier into the second of said positions when said latch is retracted.

5. A baling press comprising a box, filler pieces within the box, means securing the filler pieces to the box, and adjustable spacers positioned between the filler pieces and box.

6. A baling press comprising a box, a lever pivotally supported above and extending across the box, a plunger, and means for supporting the plunger for movement into operative position with respect to the box and lever and for movement into inoperative position with respect to the box and lever.

7. A baling press comprising a box, filler pieces arranged within the box for adjustment with respect to each other, adjustable means for securing the filler pieces against movement in one direction, and means removably positioned within the box for securing the filler pieces against movement in the opposite direction.

8. A baling press comprising a box, a carrier, a plunger slidably supported by the carrier, means mounted on the carrier and connected to the plunger to support the latter in raised position, a plunger actuating lever consisting of sections adjustably connected to permit the pressure applied to the plunger to be varied, and a weight secured to the lever for normally supporting it in elevated position.

In testimony whereof I affix my signature.

ABE WEST.
